AUTOMATIC STAMPING APPARATUS
James G. Keramas, 57 Kilby St., Woburn, Mass.
Filed Nov. 3, 1964, Ser. No. 408,601
11 Claims. (Cl. 101—44)

This invention relates to apparatus for stamping, marking or printing coded indicia on each of a plurality of articles such as containers of food or the like.

It has heretofore been proposed, as in U.S. Patent 3,018,720 of January 30, 1962, to Nichols, to stamp each of a plurality of containers continuously advancing on a conveyor, by means of a stamping head which rolls slightly upon contact to avoid blurring due to the continuous motion of the container. The repeated application of ink to the stamp, has also presented a problem in the prior art, the ink pad being mounted on a pivoted arm to move into the path of the stamping head in the above mentioned patent and in U.S. Patent 2,787,950 to Dorsch of April 9, 1957.

In this invention, the carrier continuously advances a line of abutting containers but the line is temporarily halted, when each successive container is sensed just in advance of a stamping station, by clamping of the preceding container then at the station. Where the carrier is a conveyor belt, the belt continues to advance by slippage under the halted line of containers, the line resuming advance each time the clamp releases. While each container is at a halt, at the stamping station, a stamping head, which normally faces away from the containers in engagement with a stationary ink pad, is first advanced while turning through 180° and then further advanced in a straight line while held against turning, until it strikes and stamps the container without danger of blurring or smudging. All of the clamping and stamping operations are performed by air cylinders and pistons by means of an air switch, the switch being actuated by an article actuated arm so that there is no dependence on escapement mechanisms, photo cells, solenoids or electric switches and so that a positive, dependable, coding is achieved.

The principal object of the invention is to provide a rugged, low cost, marking apparatus for applying code numbers, or prices, individually and successively to a line of abutting containers wherein mechanically movable parts are at a minimum, no movable gate is required to hold back the containers and wherein actuation is pneumatic rather than electric.

Another object of the invention is to provide a stamping apparatus which can be affixed to a processing line to stamp containers which are non rigid, of cubical or cylindrical configuration, provided with recessed or concave bottoms, or wherein the side, top or bottom walls require code indicia, all by simple adjustments of the parts of the apparatus.

A further object of the invention is to provide novel pneumatic mechanical means for sensing each container, yieldably clamping and holding down the container and yieldably, but clearly stamping the container, whereby inflammable or volatile goods may be marked with little danger of explosion and no damage is imparted to delicate containers.

A still further object of the invention is to provide automatic feed, clamp, mark and release stamping apparatus having an accessible and removable ink pad, which is not mounted on a moving part of the apparatus, so that the pad may be refilled with ink, or replaced, while the apparatus is in use.

Other objects and advantages of the invention will be apparent from the claims, the description of the drawings and from the drawings in which:

FIGURE 1 is a side elevation of the apparatus of the invention;

FIGURE 2 is an end elevation thereof;

2

FIGURE 3 is a diagram of the pneumatic control circuit;

FIGURE 4 is an enlarged, side elevation of the stamp housing and base;

5 FIGURE 5 is a front elevation, with the cover removed, of the device shown in FIGURE 4;

FIGURE 6 is a fragmentary, side elevation in section on line 6—6 of FIGURE 5 showing one position of the stamping head;

10 FIGURES 7, 8 and 9 are views similar to FIGURE 6 showing other positions of the stamping head during the stamping cycle, and

FIGURE 10 is a diagrammatic side elevation of another embodiment of the invention.

15 As shown in the drawings, the automatic stamping, marking or printing apparatus 30 of the invention preferably includes a suitable frame 31, supporting an electric or air motor 32 and reducer 33. Motor 32 is of the explosion proof type.

Carrier means 34 preferably comprises a pair of smooth substantially frictionless faced, endless belts 35 and 36, trained around a double drive pulley 37 on the shaft 38 of reducer 33, and around double, idler pulleys 41 and 42, each at an opposite end 43 or 44 of frame 33. Suitable additional idler, or tension pulleys, 45 and 46 are mounted on frame 33.

20 The parallel, spaced apart, horizontal stretches 47 and 48 of the belts 35 and 36 thus establish a path, or container line, 51, extending from the feed end 43 to the discharge end 44 of the apparatus 30, the path including a stamping station 52. The drive of belts 35 and 36 is continuous, rather than intermittent so that a plurality of containers 53 or other articles to be stamped, marked or printed, when deposited with the bottoms 54, thereof straddling the stretches 47 and 48 and supported at each opposite underside thereon, will be advanced continuously along the path. There are no spacing or registration abutments on the belts 35 and 36 so that the feed is untimed and the apparatus is article actuated. When the line of

25 containers is temporarily halted, by the sensing and clamping of each successive container 53 at the stamping station, the containers in rear are halted, the belts slip under the bottoms thereof to continue advancing at the predetermined speed and the containers beyond the stamping station continue to advance to the discharge end 44. By 30 adjusting the time period, during which stamping takes place, the containers which are preferably in abutting relationship in advance of the stamping station can be spaced at desired distances apart in rear of the stamping station.

35 Suitable laterally adjustable side guides 55 and 56 are supported on frame pieces such as 57, to slidably engage and guide the opposite side faces 58 and 59 of the containers 53, which may be food or aerosol cans, bottles, plastic containers or the like, such as must be coded and priced for supermarket use. Set screws 60, or any other well known expedient, may be used for lateral and vertical adjustment of guides 55 and 56. The speed of the belts 35 and 36, is also adjustable, it having been found that the apparatus of the invention performs accurately 40 at up to 250 complete stamping cycles per minute with belt speed adjusted accordingly, for example up to 250 feet per minute.

Sensing means

45 The possible danger of explosion due to electric circuitry including photo cells or tubes, limit switches, solenoids, etc. in the vicinity of the stamping station when containers of inflammable material such as paint are being coded has been avoided in this invention by using pneumatic-mechanical means exclusively at the station 52. As shown, the sensing means 63 comprises a pneumatic, switch, or valve, 64 mounted on a side guide such as 56 and having an actuating arm, or trigger, 65 nor-

mally in the path of the containers 53 to be actuated by impact with each successive container. The pivoting of the arm 65 by contact with each successive article arriving at stamping station 52, opens air valve 64 to connect the source of air pressure 66 with air conduit 67 leading to the pneumatic actuation system. The source 66 may be a compressor and tank, or conventional mill air supply, suitably regulated at regulator 172 to preferably about 35 to 45 p.s.i. at a rate of .126 to .218 cubic feet per minute.

Clamping means

Combined clamping, holddown and halting means 70 is provided, comprising at least one clamping element 71 and preferably two, oppositely disposed clamping elements such as 71 and 72. Each clamping element is normally positioned alongside, and outside, the path of containers 53 and is of suitable construction to engage the adjacent side face 58 or 59 of the particular type container to be marked. Usually such containers will be cylindrical so that each element 71 or 72 while flat has a flat inner face 73 of soft material such as foam rubber which conforms with, and compresses to, the configuration of the container. Where a single clamping element is used, it may clamp the container sidewise against a side guide, or downward against the carrier means, but two laterally movable elements, or jaws moving in a horizontal plane, in parallelism with the horizontal plane of the spaced apart belts of the carrier, are preferred. Each clamping element 71 or 72 is mounted on a piston rod such as 74 or 75, each piston rod being slideable in an air cylinder 76 or 77, the cylinders being adjustably mounted on suitable adjustable brackets 78 or 79 depending from a side guide 55 or 56.

The piston rods and cylinders of each clamping element are termed the first, power actuated plunger means 80 herein, since similar plunger means is also used for the stamping head. Preferably the stroke of each movable clamping element 71 and 72 is about one quarter of an inch, the inward travel thereof into contact with the side faces of each container at station 52 exactly positioning the container above the stamping station straddled by the container and belts. The container is not only halted by the elements, together with the line of succeeding containers, but the pressure of the foam rubber faces tends to hold down the container against the impulse impact of the upwardly travelling stamping head.

Stamping means

The stamping means 82, is mounted along path 51 at stamping station 52, preferably below the path and in the space 83 between the parallel horizontal stretches 47 and 48 of carrier means 34, in the embodiment illustrated in FIGURES 1 and 2. Stamping means 82 includes a movable stamping head 84, having coded indicia 85 thereon, in the form of rubber printing type 86, slidably mounted in a dovetail groove 87, so that it may be easily changed by substitution through the opposite open ends of the groove.

Preferably stamping means 82 includes a base 90, affixed under the bed plates 91 of the frame 31 to depend vertically downwardly below the path 51 and having a slot 92 in one side wall 93.

The stamping head housing 94 includes an integral, laterally projecting boss 95, which passes through the slot 92 into the base, there being a thrust screw 96 rotatable in the base and threaded in the boss for adjusting the relative positions of the housing and base, as well as a suitable locking set screw 97. The housing may thus be advanced or retracted on the base to enable the stamping head to reach into the path of the containers to desired distances.

The housing 94 includes a removable cover 98, over a plunger compartment 99 and a pair of parallel, upstanding, spaced apart slotted guides 101 and 102 which extend normal to the path of the containers when the

means 82 is normal thereto. A laterally slideable tray 103, containing an ink pad 104, is mounted in grooves 105 and 106 at the inner end of guides 101 and 102, so that the type 86 and indicia 85 on head 84 will engage the pad at the terminus of the retraction stroke. The ink pad is therefore stationary and outside the path of the containers, but easily removable for substitution while the device is in operation. A spring loaded detent 107 is provided to lock the head in advanced position so that ink can be supplied to the pad when necessary, for example at the end of a run or at the end of a work day or to change pad 104, type 86 or indicia 85.

On the outside of the guides 101 and 102, the arms 108 and 109 of a yoke 112 are slideable, there being a pivot pin 113 extending between the terminal ends 114 and 115 of the arms which travels up and down in the slots of the guides. The head 84 is pivotally mounted on pin 113 and camming mechanism 116 is provided on one side, to turn the head through an angle of 180° proximate the ink pad portion of its stroke, while guiding mechanism 117 is provided on the other side to prevent turning of the head proximate the container portion of its stroke.

Camming mechanism 116 includes an integral lug depending from one side of head 84 and having a pair of teeth 118 and 119 arranged to engage a pair of laterally projecting inwardly extending, pins 120 and 121 on the inner face 122 of guide 102. The pins and teeth cause the stamping head 84, when advanced by the yoke in the guides, to turn from normal ink pad engaging position to container impacting position in the preliminary portion of the stroke and before reaching the path of the containers. The slot 123 in guide 102 accommodates only the pivot pin 113.

Guiding mechanism 117 includes an integral slider 125 depending from, and projecting laterally outwardly from head 84, the slider being of angular configuration and slideable in the slot 126 in guide 101. A curved recess 127 in one edge of slot 126 permits the slider 125 to turn when the head 84 is turned by the camming mechanism, but upon further advance of the head by the yoke and toward the path 51 of the containers, the close tolerance of the angular slider in the slot keeps the head on a rectilinear path exactly normal to the path (FIGURES 6, 7, 8 and 9).

The second power actuated plunger means 130 is similar to plunger means 80 and comprises an air cylinder 131, and air piston 132, the piston 132 being fixed to the yoke 112, to turn and advance the head.

Control circuit means

As shown diagrammatically in FIGURE 3 the pneumatic circuit, or system, 133 which includes, and is actuated by, the switch 64 through conduit 67, includes the time delay, diaphragm type valve 134 which permits pressurized air to pass first to the cylinders 76 and 77 through air conduits 135 and 136 to advance the clamping elements 71 and 72 for gripping a container, and then permits pressurized air to pass to the cylinder 131 through conduit 137 to advance the piston 132, yoke 112 and stamping head 84 through its longer stroke of about 1½ to 2 inches. After the clamping, halting and stamping cycle is completed with a clear precise code stamped on a container 53, a by-pass to the valve 134 closes the valve and opens the system to the atmosphere at outlet port 138, thereby permitting sensing air valve 64 and arm 65 to return to normal position ready to sense the next successive container in the line. A pressure control valve 141 is interposed in conduit 137, of a commercially available type such as the "Colorflow" of Manatrol Co., Cleveland, Ohio, so that the impact of the head 84 may be light or heavy and may be adjustable during operation for imprint control.

As shown diagrammatically in FIGURE 10, the carrier means of the invention may be a downwardly inclined

plate, or trough, 150 having a substantially frictionless bottom 151 formed by a pair of parallel, nylon or Teflon strips which straddle a stamping station 152. The clamping means 153, is a disc-like plate 154 having a flat lower face 155 and actuated by first plunger means 156 corresponding to means 80. An air switch 157, stamping means 158 and control circuit means 159 are all similar to switch 64, means 82 and circuit means 133 respectively.

As shown diagrammatically in FIGURE 3 the arm 65 of pneumatic switch 64, is provided with a roller 160 for engaging the articles, and is pivoted at 161, there being a pivoted link 162 pivoted at 163 and having a roller 164 engaged by arm 65. Link 162 engages the push button 165 of the switch, the button having a return spring 166 which restores the parts to normal position. The outlet port of the switch is designated 167.

Each piston 74, 75 and 132 has a suitable return spring such as 168 for returning it to normal position when air pressure is released.

The diaphragm valve 134 is of the type designated Model 125A of the Humphrey Corporation and is commercially available. The check valve 170, filter 171, pressure regulator 172, gauge 173, and lubricator 174 are also commercially available and well known.

The time delay by-pass 175 includes the conduit 176, flow control valve 177 and the elongated portion 178 so that air passes into one side of valve 134 at about two c.f.m. from conduit 67 to actuate the system, but a portion is by-passed into conduit 176, reduced to about .1 c.f.m. by valve 177, and, after a predetermined delay due to the length of the portion 178, enters the other side of valve 134 to deactivate the same and permit spring return of the parts to normal position.

I claim:

1. Apparatus for automatically stamping coded indicia on a plurality of substantially identical containers, said apparatus comprising;

carrier means movable in a predetermined plane, said means supporting and advancing said containers individually and successively, in aligned, abutting relationship along a path which includes a stamping station;

sensing means mounted along said path and including article actuated means in said path, in advance of said station for sensing the arrival of each successive container at said station;

container clamping means mounted at said station, said means including at least one clamping element movable in a predetermined plane and adapted to engage the adjacent portion of a container at said station;

first power actuated plunger means operably connected to said clamping element and responsive to said sensing means for moving each said element into said path to temporarily halt, and hold down, each successive container at said station, and thereby halt, the abutting containers in rear thereof;

stamping means, mounted below said station, said means including a stamping head bearing said coded indicia, said head being movable in a plane normal to the plane of said carrier means and an ink pad, said indicia and pad being normally in inking engagement outside of said path;

second power actuated plunger means operably connected to said head and responsive to said sensing means for moving said head upwardly into said path to apply said coded indicia to each successive container only after said container has been clamped temporarily halted and held down at said station, and

control circuit means including a source of power, said sensing means, said first plunger means and said second plunger means for energizing each said means in a predetermined sequence.

2. Apparatus as specified in claim 1 wherein said carrier means is a power driven, continuously moving, endless belt conveyor having a horizontal stretch extending along said path for conveying said line of said containers therealong in abutting relationship;

said conveyor having a smooth substantially frictionless, surface to continue moving under the line of containers supported thereon when said line is temporarily at rest during each successive stamping at said station and the plane of movement of each said clamping element is in parallelism with the plane of movement of said horizontal stretch of said conveyor.

3. Apparatus as specified in claim 1 wherein said carrier means is a downwardly inclined, substantially frictionless trough adapted to support a line of abutting containers therein, and

said clamping element is a disc-like, soft faced element poised above said path and trough but movable downwardly in a plane normal to the inclined plane of said trough each successive element against said trough in a position of rest at said station.

4. Apparatus as specified in claim 1 wherein said carrier means is a pair of spaced apart, smooth faced endless belts with parallel horizontal stretches extending along said path to straddle said stamping station while advancing a line of abutting containers therealong, said stamping head is operable in the space between said pair of belts to stamp the bottom face of each successive container at said station, and

a pair of said clamping elements are each disposed on an opposite side of said container path, at said station to move into said path and grip the opposite side faces of each successive container in said line to halt and hold down the same during said upwardly directed stamping at said station.

5. Apparatus as specified in claim 1 wherein said sensing means is a pneumatic switch including an actuating arm in the path of said containers;

said first plunger means includes a pneumatic cylinder and piston for moving each said clamping element; said second plunger means includes a pneumatic cylinder and piston for moving said stamping head, and said control circuit means includes a source of air under pressure, pneumatic time delay means for actuating said first plunger means prior to the actuation of said second plunger means and air conduits connecting said switch and pneumatic cylinders together.

6. Apparatus as specified in claim 1 wherein said stamping means and second plunger means include co-operable camming mechanism for turning said stamping head through an angle of 180° when said head is moving toward and away from the vicinity of said ink pad and co-operable guide mechanism including a guide having a recessed slot and an angular slider movable in the slot for holding said stamping head against turning when said head is moving toward and away from the vicinity of a container at said station.

7. Apparatus as specified in claim 1 wherein: said plunger means are air operated, the source of power of said circuit means is air under pressure and said control circuit means includes an elongated bypass conduit for de-energizing said circuit at a predetermined time after each energization thereof.

8. In an automatic stamping, marking or printing apparatus;

a pair of spaced apart, smooth-faced, conveyor stretches advancing horizontally and continuously along a path including a stamping station, said conveyor carrying a line of abutting identical containers to be stamped; sensing means mounted along said path, in advance of said station to sense the arrival at said station of each successive container carried on said conveyor; at least one clamping element movably mounted along

- side said path, at said station, said element having a flat inner face of soft, foam rubber-like material, movable horizontally to enter said path, strike against a side of, resist vertical upward movement of and temporarily halt each said container so sensed by said sensing means, said container temporarily halting the advance of all abutting containers in rear thereof;
- a stamping head movably mounted below said path, at said station, in the space between said belts, said head being movable vertically to enter said path, strike against the bottom of, and stamp each said container so sensed and halted at said station, and pneumatic control and actuation means responsive to said sensing means and operatively connected to said element and head, said means including pneumatic time delay means for first actuating said clamping element and then actuating said stamping head on each successive container sensed by said sensing means.
9. An automatic stamping apparatus for applying coded indicia individually and successively to a plurality of articles continuously advancing in abutting relationship along a path, said apparatus comprising:
- a housing having a pair of parallel, spaced apart up-standing, slotted guides adapted to be mounted substantially normal to said path, the slot in one said guide having a slider recess;
- a yoke having a pair of arms each mounted to slide outside of one of said guides, said yoke having a pivot pin extending between the terminal ends of said arms and slideable in the slots of said fixed guides;
- a stamping head, bearing coded indicia at one end and pivotally mounted on said pivot pin at the other end, said head including a toothed lug depending from one side thereof;

5

10

15

20

25

30

35

- a pair of pins extending laterally and inwardly midway of one of said guides to engage said toothed lug, when said yoke moves said head midway of said slots and turn said head through an angle of 180°;
- a slider depending from the other side of said head and slideable in the recessed slot in the adjacent guide, said slot preventing turning of said head when said yoke moves said head along the terminal ends of said slots, but said recess permitting such turning midway of said slots and
- a fluid actuated plunger connected to said yoke for moving the same along said guides to turn and advance said head into contact with said articles.
10. Apparatus as specified in claim 9 plus an ink pad normally fixed between said guides in position to engage said indicia when said head is in retracted position, and tray means supporting said pad and slidably mounted in said guides for enabling said pad to be replaced.
11. Apparatus as specified in claim 9 plus a base adapted to be fixed alongside the said path, said base having a slot in one side wall thereof;
- a boss extending laterally from said housing through said slot into said base, and
- a thrust screw rotatable in said base and threaded in said boss for adjusting the relative positions of said housing and base.
